UNITED STATES PATENT OFFICE

HENRY J. WIEGAND, OF MILWAUKEE, WISCONSIN.

ELECTRICAL CONTACT.

1,119,209.

Specification of Letters Patent.

Patented Dec. 1, 1914.

Application filed March 13, 1914. Serial No. 824,547.

To all whom it may concern:

Be it known that I, HENRY J. WIEGAND, a citizen of the United States, residing at Milwaukee, in the county of Milwaukee and State of Wisconsin, have invented new and useful Improvements in Electrical Contacts, of which the following is a full, clear, concise, and exact description, reference being had to the accompanying drawing, forming a part of this specification.

This invention relates to electrical contacts, and this application is a continuation of my application filed August 2, 1912, and issued April 14, 1914, Patent No. 1,092,880, 15 as to all the common subject matter of the two applications.

The various objects and advantages of the invention will appear hereinafter in connection with the description of the two embodiments thereof illustrated in the accompanying drawing, wherein,

Figure 1 is a perspective view of one form of contact, Fig. 2 is a similar view of the second form of contact, Fig. 3 is a bottom plan view of the latter; and, Fig. 4 is a sectional view of the contact shown in Fig. 2 mounted on a suitable base.

The contacts are particularly adapted for use in rheostats wherein they are connected to resistance elements and with said elements are embedded in plastic material, but having their surfaces exposed to be engaged by a suitable controlling member. Each contact comprises in general, a sheet metal punching having a flat contacting surface with depending lugs for seating the same on a base and laterally extending lugs for connection with suitable conductors.

Referring more specifically to the drawing, there is shown in Fig. 1 a contact formed of an oblong metal strip punched to substantially inverted U-shape thereby providing a raised flat contact surface 1 with depending end walls or supports 2. These end portions are slotted longitudinally and the metal at one side of the slits, preferably at diagonally opposite corners of the contact, is curled upwardly to provide lateral ears 3. The metal at the other side of the slits extends downwardly and constitutes a pair of lugs 4.

Fig. 2 illustrates a contact having the general features of that shown in Fig. 1, and having, in addition, side walls 5. In this form, the contact is stamped from a substan-

tially square sheet having restricted slits 6 to facilitate its stamping. These slits, however, are substantially closed when the contact is punched. In this embodiment, also the lugs 3 are projected at right angles to the end walls 2 and provide supporting bases 7 flush with the free margins of the contact.

One manner of mounting the contacts is shown in Fig. 4 wherein a suitable insulating base 8 is provided with recesses 9 to receive the depending lugs 4 of the contacts. These recesses are preferably of a depth equal to the length of the lugs 4 so that the button is firmly seated on the base when its lower margins and its lateral supports 7 rest thereon. Resistance wires 10 are connected to the attaching ears 3 of the contact and the same then covered with a suitable insulating cement 11, or other plastic material, which anchors the contact to the base and provides a protective casing for the resistance element. However, the raised surface 1 of the contact protrudes slightly above the material 11 and thus furnishes a contacting face with which a controlling member may engage.

The contact described is extremely rigid and is adapted for secure attachment to a base without the use of screws or other special fastening means. Furthermore, the device is exceedingly simple and cheap to manufacture and carries an effective anchoring portion to be held by the insulating compound 11. It is also to be noted that the contacts may be arranged closely adjacent to each other since the lugs 4 and ears 3 are at opposite ends, and the sides thereof remain unobstructed and sheer.

What I claim as new and desire to secure by Letters Patent is:

1. A sheet metal contact having substantially parallel end portions and an intermediate contact portion, said end portions being longitudinally divided to provide each with a connecting lug and a lug to engage a supporting base.
2. A sheet metal contact of substantially inverted U-shape in longitudinal section and having its ends slotted to provide each with two lugs, one of said lugs being in the plane thereof to project into a supporting base and the other being offset therefrom for circuit connection.
3. A sheet metal contact of substantially

inverted U-shape in longitudinal section and having its ends slitted to provide each with two lugs, one of said lugs being in the plane thereof to project into a supporting base and the other offset therefrom, the lugs at one end of said contact being in reversed relation with respect to those at the other end.

4. A sheet metal contact of substantially inverted U-shape in longitudinal section and of substantially uniform width throughout, said contact being provided with depending supporting lugs and an end connection lug.

5. As an article of manufacture, a sheet metal contact provided with parallel end portions and an intermediate portion having sheer sides, said end portions serving to support said intermediate portion in an ele-

vated position and also serving for connection of said contact in an electric circuit.

6. As an article of manufacture, an electrical contact comprising a sheet metal stamping provided with a substantially rectangular contacting surface and depending end and side walls, certain opposed walls thereof being sheer throughout and the other opposed walls having offset lugs for connection with suitable conductors.

In witness whereof, I have hereunto subscribed my name in the presence of two witnesses.

HENRY J. WIEGAND.
